(57) **CLAIM**

The ornamental design of an impact tool body portion, as shown and described.

DESCRIPTION

FIG. 1 is an isometric view of an impact tool body portion showing my design;

FIG. 2 is a left side view of FIG. 1;

FIG. 3 is a right side view of FIG. 1;

FIG. 4 is a front view of FIG. 1;

FIG. 5 is a top view of FIG. 1; and,

FIG. 6 is a bottom view of FIG. 1.

The broken lines which define the bounds of the claimed design form no part thereof.

The surface(s) or portion(s) of the article not shown in the drawing or described in the specification form(s) no part of the claimed design.
